United States Patent Office

Des. 177,168
Patented Mar. 20, 1956

177,168

CENTRIFUGAL EXTRACTOR FOR LAUNDRIES

Carl H. Clement, Jr., Perrysburg, Ohio, assignor to Bock
Laundry Machine Co., Toledo, Ohio, a corporation of Ohio

Application January 18, 1955, Serial No. 34,039

Term of patent 14 years

(Cl. D49—1)

FIG. 4.

Fig. 1 is a top front perspective view taken from the right showing my new design;

Fig. 2 is a similar view taken from the left thereof;

Fig. 3 is a rear perspective view thereof, and

Fig. 4 is a top plan view thereof.

The dominant features of my design reside in the portions shown in full lines.

I claim:

The ornamental design for a centrifugal extractor for laundries, substantially as shown and described.
